UNITED STATES PATENT OFFICE.

CHARLES F. ROOT AND BYRON O. CONN, OF MANSFIELD, OHIO.

PAPER TURNING-IN AND PASTING MACHINE.

SPECIFICATION forming part of Letters Patent No. 741,550, dated October 13, 1903.

Application filed August 21, 1902. Serial No. 120,587. (No model.)

To all whom it may concern:

Be it known that we, CHARLES F. ROOT and BYRON O. CONN, citizens of the United States, residing at Mansfield, in the county of Rich-
5 land and State of Ohio, have invented a new and useful Automatic Paper - Pasting Machine, of which the following is a specification.

Our invention relates to a paper turning-in and pasting machine which is especially adapted to be used in the manufacture of paper boxes. It is well known to those skilled in the art that in the manufacture of such boxes the exterior of the strawboard which
10 constitutes the body portion of the box is covered with paper or other suitable material for the purpose of giving the box a neat and attractive appearance, as well as affording additional strength and rigidity thereto. In
15 covering the box the paper or other covering material is pasted to the exterior thereof, leaving a projecting margin or overplus of the covering material extending beyond the upper edges of the box and the lower edges of
20 the cover.

The principal objects of our invention, therefore, are to provide a machine which will automatically perform the operation of bending over and pasting the overplus or
25 margin of the covering material to the interior surface of the box; secondly, to reduce the cost of manufacturing such boxes, and, thirdly, to insure uniform and perfect work. To this end we accomplish such objects by
30 means of an automatically-operating and adjustable mechanism more fully described hereinafter and particularly pointed out in the claims.

In the accompanying drawings, Figure 1 is
40 a perspective view of the complete machine. Fig. 2 is a view in vertical cross-section of the machine. Fig. 3 is a top plan view of the bed-plate and carriage, showing the method of operating the clutch mechanism, portions
45 being removed to better disclose the operating mechanism. Fig. 4 is a top plan view of the carriage, showing the adjustable clamps for retaining the box in position. Fig. 5 is a view in vertical cross-section of the carriage,
50 taken on line $\alpha\alpha$ of Fig. 4. Fig. 6 is an end view of the carriage-base, disclosing the journaled trip-shaft. Fig. 7 is a view in vertical

cross-section of the carriage-base, taken on the line $\alpha\alpha$ of Fig. 6. Fig. 8 shows a detailed side and end view of one of the folding-fingers, disclosing the spring-pressed pin. Fig. 9 is a view in front elevation of the tilting bar and fingers. Fig. 10 is a view in side elevation, partly in section, of the tilting-bar support, the tilting bar, and the finger. Fig. 60 11 is a detailed perspective view of one of the adjustable box-clamps, and Fig. 12 is a detailed perspective view of the trip bolt and plate.

The bed-plate or table 1 is supported by 65 legs or standards 2 and constitutes the body portion of the machine. The center of the table is provided with a longitudinally-extending slot or way 3. The one shown is V-shaped; but any other suitable conformation 70 may be used.

Received within the slot 3 and adapted to reciprocate therein is a carriage comprising a base portion 4, conforming to the shape of the slot or way 3. This base portion has a 75 flat top 41 and is provided with a longitudinally-extending opening or groove in its lower portion, across which opening and journaled in the walls thereof is a trip-shaft 8. This shaft is provided with pairs of oppositely-extending pins 77; projecting radially from the periphery of the shaft 8. A stud 17, located equidistant between the pairs of pins 77, is secured to and projects outwardly from the shaft 8, and to the outer end of this stud is 85 secured a spring 18, the opposite end of the spring being secured to the base portion of the carriage. This arrangement serves to normally retain the pins 77 in vertical position.
90

Located centrally of and projecting vertically upward from the top 41 of the carriage-base 4 is a cylindrical shaft 40, and received upon this shaft is the carriage proper, comprising a hollow sleeve 12, surrounding the 95 shaft 40 and the oppositely-extending slotted arms 11 11, secured to and extending radially from the sleeve 12. The outer ends of these slotted arms 11 11 are rounded off, and depending pins 45 are secured to the ends of two 100 of the oppositely-extending arms for a purpose hereinafter set forth. Received upon the oppositely-projecting arms are the box-clamps 14 14, each consisting of a weighted

body portion 14', provided with slots for the reception of the slotted arms 11 11 and also provided with a threaded aperture 14". The body portion is provided with lateral extensions having L-shaped upwardly-extending gripping-arms 14^a 14^a formed thereon to engage the side of the box to be covered. Each of the four radially-extending slotted arms carries one of these box-clamps. Suitably-supported differentially-threaded adjusting-screws 15 15 are received in the screw-threaded apertures 14^a 14^a of the box-clamps, one screw engaging the apertures of two opposite clamps, the right and left screw-threads on the screws permitting the simultaneous adjustment of each pair of box-clamps toward and from each other, the box-clamps being equidistant from the center of the carriage proper. A spring 59, suitably secured to brackets 59' 59', secured to the base portion of the carriage, is adapted to have frictional contact with the exterior of the sleeve 12 to regulate and prevent a too free rotation.

Four equidistant rods 42 42 project radially from the sleeve 12 of the carriage, and located within the arc of movement of the rods is an L-shaped post 43, extending upward from the bed-plate 1, upon the laterally-projecting portion of which post is journaled a tapering wedge-shaped plate 44, with which plate the rods 42 42 are adapted to contact in their forward travel—that is, toward the left of the drawing Fig. 1.

Located at either end of the slot or way 3 is a post 10, adapted to enter the slots in the divided arms 11 11 and engage the box-clamps 14 14 to serve as a stop for the carriage and also to guide and retain the carriage in direct alignment.

40 The movement of the carriage is caused by a sprocket-chain 6 passing over sprocket-wheels 39 39, keyed upon shafts 39' 39', journaled at each end of the body portion of the machine beneath the bed-plate 1. This chain passes above and below the trip-shaft 8 between the pins 7 7 7 7, and carried by one of the links is a laterally-extending trip-pin 5. This pin is adapted to engage the vertically-extending pairs of pins 7 7, the tension of the 50 spring 18 being such as to prevent the rotary movement of the trip-shaft 8 until the post 10 engages one of the box-clamps 14. Hence the carriage will travel in the way 3 until such engagement occurs, whereupon the 55 spring will yield, permitting the shaft 8 to partially rotate and allowing the pin 5 to pass over the ends of the pins 7 7. The shaft 8 is then returned to its normal position by means of the spring 18. The carriage of course remains at the end of the way or at its adjusted 60 limit of movement, which limit is controlled by means of the adjusting-screws 15 15, which regulate the distance of the box-clamps 14 14 from the center of the carriage, according to 65 the size of the box which is to be held by the clamps.

Projecting above and below the bed-plate

1 at each end thereof are a pair of supporting-shafts 52 52, the inner sides of which are provided with rack-teeth 53 53, adapted to mesh with and bear against gear-wheels 54 54, keyed upon shafts 51 51, journaled in the supports of the bed-plate. The engagement of the rack-teeth with the gear-wheels serves to retain the supporting-shafts in vertical position and aids in the adjustment thereof, set-screws 55 55 being located in the bed-plate 1 and adapted to engage the shafts 52 52 to retain them in their adjusted positions. Idle rollers 50 50 are loosely journaled on the 80 shafts 51 51 and bear against the lower portion of the sprocket-chain 6 to maintain it at a uniform tension and at a uniform distance from the upper portion. A supporting-bar 26 is secured to and supported by the ends of each pair of supporting-shafts in any suitable manner, the upper face of the bars 26 26 being rearwardly inclined, and downwardly projecting ears 25 25 are secured to the lower surface of the bars 26 26. The front faces of these bars 26 26 are provided with grooves 16 16 for the reception of the projecting ends 14^a 14^a of the box-clamps 14 14 in order that the box carried thereby may be brought against the faces of the bars 26 26, so that such faces will provide a rigid platen against which the edge of the box is pressed when the fingers are forced against the interior thereof during the folding and pasting of the surplus margin. Tilting bars 29 29 are connected to the bars 26 26 by means of hinges 30 30, and projecting upwardly from each bar 29 are a pair of ears 28 28. Each bar 29 supports a plurality of folding-fingers 31 31 of substantially right-angular shape in cross-section, 105 the tilting bar received in the recess of the fingers formed by such conformation. The bearing-surface of the body portion of each finger is provided with a recess for the reception of pins 37, behind which are located springs 38 for forcing the pins outward. These pins bear upon the upper face of the tilting bars 29, which bars may have slight depressions, as 37' 37', for the reception of the outer ends of the pins 37 37. The upper 110 faces of the fingers 31 31 are provided with notched recesses 34 34, and standards 35 35, secured to the supporting bars 26 26, are adapted to carry retaining-bars 33 33, the lower edges of which are received in the notches 120 34 34 to retain the fingers in position upon the tilting bar. The fingers may be moved laterally of the tilting bar beneath the retaining-bar to conform to the width of the box being covered and permit the edges of 125 the box to pass between adjacent fingers. The rearward inclination of the upper face of each tilting-bar support 26 26 naturally operates to throw the tilting bars and the fingers carried thereby at an angle to the bed-plate 1. The folding-faces 57 of the fingers are thus located at a slight angle to the bed-plate 1 and to the box supported in the carriage, which inclination permits the edge of

the box to pass thereunder and bends the surplus margin of the covering material into a position at right angles to the side of the box preparatory to folding it downward and pasting it to the interior surface of the box.

Each pair of supporting-legs 22 of the bed-plate or table is connected by means of brackets or bars 58 58, and passing through an opening in each bracket or bar is a post 22, to the upper end of which is pivotally secured a bell-crank lever 24, one end of which lever is pivotally connected to the ears 25 of the tilting-bar support 26, the other end of the bell-crank lever being pivotally connected to the ears 28 on the tilting bar by means of a link 27. An adjustable collar 23 is carried by one of said posts 22, and a support 20, also carried by the bracket or bar 58, bears at its upper end a pivotal double yoke 19, one end 21 of which embraces the post 22 beneath the adjustable collar 23. The opposite post 22' is similar in every respect to post 22, with the exception that it carries a combined collar and yoke 23', adjustably secured thereto by means of a set-screw.

One of the shafts 39', to which are keyed the sprocket-wheels 39 39, projects outward from the machine and has loosely secured thereon a drive-wheel or clutch-pulley 60, provided with any suitable clutch mechanism 49. A lever 47 is pivotally supported on the bed-plate, one end of the lever being connected to the clutch mechanism 49. Secured to the free end of the lever is a plate-spring 46, with the inner end of which one of the pins 45, carried by the projecting slotted arms 11 11, is adapted to contact as the carriage completes half a revolution upon the shaft 40, whereby to move the lever 47 and disengage the clutch from the drive-wheel 60. Notches 61 are provided to receive the edges of the clamps when the machine is used in pasting shallow boxes or covers.

The operation of our machine may be gathered from the foregoing; but a brief description is here given. The box being covered is secured in the box-clamps 14 14, which are adjusted by means of the screws 15 15. The machine is then started by moving the pivoted lever 47 in such manner as to throw the clutch member 49, slidably keyed to shaft 39, into mesh with the other clutch member on loose drive-wheel 60, whereupon the shaft 39' is rotated, together with sprocket-wheel 39, keyed thereon, over which the chain 6 passes. The movement of the chain causes the engagement of the pin 5 with the pair of projecting pins 7 7 on the shaft 8, which results in the movement of the carriage as before described. When the pin 5 slides out of engagement with pins 7 7, it is carried along and brought into contact with the free end of the double yoke 19, rocking it upon its pivotal post 20 and causing the end 21 to engage the collar 23 on post 22. This operates to raise the post 22, which by means of its bell-crank and link connection with the

tilting bar 29 swings such bar on its hinges 30 30 into the position shown in dotted lines in Fig. 2. The supporting-shafts 52 52 having been adjusted to a suitable height relative to the box carried between the clamps 14 14 and the carriage having been arrested by the stop pins or studs 10 in the proper adjusted position, so that the upper outer edge of the box contacts with the side face of supporting-bar 26, such a swinging movement of the tilting bar will cause the folding-faces 57 of the fingers to fold and press the pasted surface of the margin against the interior of the box, to which it adheres. When the free end of the yoke 19 has been sufficiently depressed by the pin 5, the latter slips by it and the weight of the tilting bar 29 and the fingers operates to swing the bar back to its normal position on the supporting-bar 26, the inclination of the bar 26, combined with the position of the tilting bar, facilitating such movement. The pin 5 on its return travel now engages the lower projecting pins 7 7 on the bar 8, and thus moves the carriage toward the opposite end of the slot or way 3. In the rearward movements of the carriage (toward the right of the drawing) the projecting rods 42 engage the tapered portion of the pivoted plate 44 on post 43 and raise it slightly, the movement permitting the passage of the rod 42 beneath the plate; but upon the forward travel of the carriage one of the rods 42 contacts with the pivoted plate and is held thereagainst until the carriage has made a quarter-turn on the stud 40. The pin 5 is disengaged from the pins 7 7, as hereinabove stated, and passes into engagement with the combined collar and yoke 23' on post 22', which is raised thereby and causes the fingers 31 31 to fold the margin over and against the interior surface of another side of the box. The spring-pressed pins 37 37 serve to permit a slight vertical movement of the fingers and aids in giving a slight pivotal movement to the fingers. This is quite important, as the corners of the box being covered (in many cases) overlap and are of double thickness. This pivotal movement also provides a means of maintaining a uniform pressure of the fingers in pasting on the cover irrespective of any irregularity of the edges or thickness of the boxes.

The adjustable collars 23 23', in combination with the adjustable bar supports or standards 52 52, provide a means of lowering and raising the tilting bar and its mechanism to conform to the size of the box being covered, and the adjustment of the collars 23 23' will regulate the throw of the tilting bar.

From the foregoing it is plain that many changes might be made in the form and arrangement of the parts described without departing from the spirit and scope of our invention, and hence we do not desire to limit ourselves to the precise construction herein set forth; but,

Having thus fully described our invention,

what we claim as new, and wish to secure by Letters Patent, is—

1. In an automatic box-covering machine, the combination with a bed-plate having a way formed therein, of a carriage adapted to reciprocate in the way, the carriage comprising a base portion received in the way, means for removably and intermittently engaging the carriage-base to cause its reciprocation in the way, a superstructure rotatably supported on the base, box-clamps adjustably secured upon the superstructure, and stops for the carriage adapted to engage the superstructure at its limits of movement.
2. In an automatic box-covering machine, the combination with a bed-plate having a way formed therein, of a carriage adapted to reciprocate in the way, the carriage comprising a base portion received in the way, means for removably and intermittently engaging the carriage-base to cause its reciprocation in the way, a superstructure rotatably supported on the base, box-clamps adjustably secured upon the superstructure, stops for the carriage adapted to engage the superstructure at its limits of movement, a trip and means on the superstructure adapted to operatively engage the trip to rotate the superstructure.
3. In an automatic box-covering machine, the combination with a suitable support having a way formed therein, of a carriage adapted to reciprocate in the way, the carriage comprising a base having an opening therethrough, a rotatable shaft extending across the opening, contact-pins projecting from the shaft, a traveling means passing through the opening, a contact-pin carried by the traveling means, the traveling pin adapted to engage the contact-pins whereby to move the carriage, tension means for removably retaining the contact-pins in engagement with the traveling pin, a superstructure rotatably supported on the base, stops for regulating the movement of the carriage, the pins adapted to disengage when the stop engages the carriage.
4. In an automatic box-covering machine, the combination with a suitable support having a way formed therein, of a carriage adapted to reciprocate in the way, the carriage comprising a base and a superstructure, the superstructure rotatably supported upon the base, the base received in the way, a shaft on the base, means for reciprocating the base in the way, the superstructure consisting of a sleeve received on the shaft, slotted arms extending radially from the sleeves, box-clamps adjustably received on the arms and stop-pins located at either end of the way, the pins adapted to be received in the slots in the arms, and contact with the box-clamps to limit the further movement of the carriage.
5. In an automatic box-covering machine, the combination with a suitable support having a way formed therein, of a carriage adapted to reciprocate in the way, the carriage

comprising a base portion, means adapted to releasably engage the base to cause its movement in the way, and a superstructure rotatably mounted upon the base, the superstructure provided with radial arms, box-clamps slidably carried on the arms, differential screws engaging opposite box-clamps whereby to simultaneously adjust the clamps and stops adapted to engage the clamps to limit the movement of the carriage.

6. In an automatic box-covering machine, the combination with a suitable support having a way formed therein, of a carriage adapted to reciprocate in the way, the carriage comprising a base portion, means adapted to releasably engage the base to cause its movement in the way, and a superstructure rotatably mounted upon the base, the superstructure provided with radial arms, box-clamps adjustably carried on the arms, radial rods projecting from the superstructure, a post stationarily supported, a pivoted plate carried by the post, the rods adapted to rock the plate when the carriage is traveling in one direction and to engage and be held by the plate when traveling in the reverse direction.

7. In an automatic box-covering machine, the combination with a suitable support, of a carriage reciprocating thereon, the carriage comprising a base and a superstructure rotatably mounted thereon, means releasably engaging the base to reciprocate the latter, driving means for such engaging means, clutch mechanism secured to the driving means, a lever for operating the clutch mechanism, a flexible means secured to the lever and means carried by the superstructure adapted to intermittently engage the flexible means to operate the clutch.

8. In an automatic box-covering machine, the combination with a suitable bed and a carriage traveling on the bed, of standards adjustably mounted on the bed, a tilting-bar support secured to the standards, a tilting bar hinged to the support, a series of fingers adjustably secured upon the tilting bar and means for operating the tilting bar.

9. In an automatic box-covering machine, the combination with a suitable bed, and a carriage traveling thereon, of adjustable standards mounted on the bed, a tilting-bar support secured to the standards, the upper face of the bar-support being rearwardly inclined, a tilting bar movably secured to the supporting-bar, a series of fingers adjustably secured upon the tilting bar and means for operating the tilting bar.

10. In an automatic box-covering machine, the combination with a suitable bed and a carriage traveling thereon, of standards adjustably secured to the bed, a tilting-bar support secured to the standards, a tilting bar hinged to the bar-support, a series of fingers supported on the tilting bar, a retaining-bar passing over and engaging the fingers to retain them in position and means for operating the tilting bar.

11. In an automatic box-covering machine, the combination with a suitable bed and a carriage traveling thereon, of standards adjustably secured to the bed, a tilting-bar support secured to the standards, a tilting bar hinged to the bar-support, a series of fingers supported on the tilting bar, spring-pressed pins carried by the fingers and engaging the tilting bar, the fingers provided with notches, a retaining-bar passing over and engaging the fingers in the notches to retain them in position and means for operating the tilting bar.

12. In an automatic box-covering machine, the combination with a suitable bed and a carriage traveling thereon, of standards secured to the bed, the standards having rack-teeth formed thereon, gear-wheels suitably mounted with which the rack-teeth mesh, set screws engaging the standards to retain them in adjusted position, a tilting-bar support mounted on the standards, a tilting bar hinged thereto, a series of fingers carried by the tilting bar and means for operating the tilting bar.

13. In an automatic box-covering machine, the combination with a suitable bed and a carriage mounted thereon, of standards adjustably supported by the bed, a tilting-bar support carried by the standards, a tilting bar hinged to the tilting-bar support, a series of folding-fingers carried by the tilting bar, a slidably-supported post, means connecting the post to the tilting bar and tilting-bar support and means for actuating the sliding post to operate the tilting bar.

14. In an automatic box-covering machine, the combination with a suitable bed and a carriage mounted thereon, of standards adapted to adjustably support a tilting bar, a series of adjustable fingers carried by the tilting bar, a slidably-supported post pivotally connected with the tilting bar, a collar adjustably mounted on the post, a yoke operating in connection with the collar, and means adapted to engage the yoke to actuate the sliding post and tilting bar connected therewith.

15. A box-covering machine comprising a bed having a way formed therein, a carriage adapted to reciprocate in the way, a shaft journaled in the lower portion of the carriage, pins projecting from the shaft, a traveling means, a pin carried thereby and adapted to engage the pins on the shaft to reciprocate the carriage, and means for causing the disengagement of the pins.

16. In an automatic box-covering machine, the combination with a bed, of a suitably-supported tilting bar mounted thereon, folding-fingers adjustably retained upon the tilting bar, a sliding post pivotally connected with the tilting bar, a collar adjustably secured on the sliding post, a yoke operating in connection with the collar, a traveling means and a pin carried by the traveling means and adapt-

ed to releasably engage the yoke to actuate the sliding post and tilt the folding-fingers.

17. In an automatic box-covering machine, the combination with a suitable bed, of a tilting bar mounted thereupon, a series of folding-fingers supported on the tilting bar, spring-pressed pins located in the fingers, the pins adapted to bear against the tilting bar upon which the fingers are supported.

18. In an automatic box-covering machine, the combination with a table having a way formed therein, of a carriage comprising a base and a superstructure rotatably mounted on the base, a shaft journaled in the base, pins projecting outwardly from the periphery of the shaft, a stud projecting from the shaft intermediate of the pins, suitably-supported tension means secured to the stud to normally retain the pins in vertical position, a traveling means, a pin carried by the traveling means adapted to engage the pins on the shaft, stop-pins stationarily located at either end of the way, and slotted arms carried by the superstructure, the stop-pins adapted to be received in the slots in the arms and regulate the travel of the carriage as well as retaining the superstructure in proper alignment.

19. In an automatic box-covering machine, the combination with a suitable bed having a way formed therein, of a carriage reciprocating in the way and comprising a base and a superstructure mounted thereon, a shaft journaled in the base, pins projecting from the shaft, traveling means engaging the pins to move the carriage, driving means for actuating the traveling means, a lever controlling the driving means, a flexible bar connected to the lever and depending pins carried by the superstructure, the depending pins adapted to engage the flexible bar to release the driving means.

20. In an automatic box-covering machine, the combination with a bed, of standards passing through the bed, rack-teeth formed on the standards, suitably-supported gears with which the rack-teeth mesh, means for locking the standards at any adjusted height, a tilting bar supported by the standards, folding-fingers carried by the tilting bar and means for operating the tilting bar and fingers.

21. In an automatic box-covering machine, the combination with a suitable support, of a tilting bar movably secured thereto, adjustable fingers mounted upon the tilting bar, a sliding post, a bell-crank lever pivotally connected to the sliding post, the bell-crank lever connected with the tilting bar, and means for actuating the sliding post whereby to operate the tilting bar.

22. An automatic box-covering machine comprising a bed having a way formed therein, a carriage adapted to reciprocate in the way, a traveling means, a pin carried by the means and adapted to releasably engage the

carriage, and tension-rollers mounted on the bed and engaging the traveling means.

23. In an automatic box-covering machine, the combination with suitable supports, of a 5 tilting bar mounted thereon, fingers carried by the tilting bar, means for moving the bar, and means on the fingers for exerting a uniform pressure against the edge of the box irrespective of any irregularity thereof.

10 24. In an automatic box-covering machine, the combination with a suitable bed having a way formed therein and a carriage reciprocating in said way, the carriage provided with box-clamps having projecting portions, of 15 standards carried by the bed, a tilting-bar support mounted on the standards and having grooves formed therein, for the reception of the projecting ends of the box-clamps, a tilting bar movably secured to the tilting-bar 20 support, a series of fingers retained upon the tilting bar and means for operating the tilting bar.

25. A paper-pasting machine comprising a movable carriage, means for actuating the 25 carriage, a superstructure supported on the carriage and adapted to carry the work, and means adapted to be actuated by the carriage-actuating means to operate upon the work carried by the superstructure.

30 26. A paper-pasting machine comprising a movable carriage, means for actuating the carriage, a movable superstructure supported upon the carriage, means engaged by the superstructure to cause the movement thereof, 35 adjustable engaging devices carried by the superstructure for holding the work, means for simultaneously adjusting the engaging devices to the size of the work and means for operating upon the work carried by the superstructure.

40 27. A paper-pasting machine comprising a movable carriage, means for moving the carriage, a movable superstructure on the carriage, and means with which the superstructure 45 intermittently engages whereby the superstructure is actuated by the movement of the carriage.

28. A paper-pasting machine comprising a movable carriage, a superstructure supported thereon, mechanism for operating upon the work carried by the superstructure and a single driving means, the driving means adapted to actuate both the carriage and the work-operating mechanism.

29. A paper-pasting machine comprising a 55 traveling member, mechanism for operating upon the work supported on the traveling member and driving means for actuating the traveling member and the work-operating mechanism successively.

30. A paper-pasting machine comprising a traveling member, mechanism for operating upon the work carried by the traveling member and a single driving means adapted to intermittently engage and actuate the traveling member and the work-operating mechanism successively.

31. A paper-pasting machine comprising a movable member, a movable superstructure supported thereon, mechanism for operating upon the work held by the superstructure, a driving mechanism and the work-operating mechanism, and means actuated by the superstructure to cause a cessation of movement of the driving means.

32. A paper-pasting machine comprising a movable member, a movable superstructure carried by the member, mechanism for operating upon the work held by the superstructure, driving means for actuating the movable member and the work-operating mechanism, means engaged by the superstructure during the movement of the carriage whereby the superstructure is actuated, and a second means engaged by the superstructure during 85 its movement for causing a cessation of movement of the driving means.

Signed at Mansfield this 10th day of July, 1902.
